(57) **CLAIM**

The ornamental design for an antenna, as shown and described.

DESCRIPTION

FIG. 1 is a first perspective view showing our design for an antenna;

FIG. 2 is a front elevation view thereof;

FIG. 3 is a rear elevation view thereof;

FIG. 4 is a top plan view thereof, enlarged to show additional detail;

FIG. 5 is a bottom plan view thereof, enlarged to show additional detail;

FIG. 6 is a left side view thereof;

FIG. 7 is a right side view thereof; and,

FIG. 8 is a second perspective view thereof.

The broken lines in the figures represent features of the antenna which form no part of the claimed design.

It is noted that the antenna as disclosed herein is suitable for use as, for example, a mobile communications antenna.
